UNITED STATES PATENT OFFICE.

EDWARDS P. JONES, OF ALAMEDA, CALIFORNIA, ASSIGNOR TO THE RISDON IRON AND LOCOMOTIVE WORKS, OF SAN FRANCISCO, CALIFORNIA.

DESIGN FOR A WATER-WHEEL BUCKET.

SPECIFICATION forming part of Design No. 26,568, dated January 26, 1897.

Application filed November 16, 1896. Serial No. 612,375. Term of patent 14 years.

To all whom it may concern:

Be it known that I, EDWARDS P. JONES, a citizen of the United States, residing in the city of Alameda, county of Alameda, State of California, have invented and produced a new and original Design for a Water-Wheel Bucket, of which the following is a specification, reference being had to the accompanying drawings, showing a part thereof.

Figure 1 is a top plan view of the water-wheel bucket. Fig. 2 is a rear end view in elevation. Fig. 3 is a cross-sectional end view in elevation on line *g g*, Fig. 1; and Fig. 4 is a longitudinal sectional side view in elevation on line *x x*, Fig. 1.

In the drawings the letters *A A'* represent the curved bottoms of the bucket, which are united by the central apex or sharp ridge *A²*. Each face or the rear or butt end *a* of the central apex is formed with the convex or swelled portion *a'*. The rear end of the central apex is united to the rear central wall or plate *B*, which central wall terminates at each side into rearwardly-extending curved rear walls *B' B²*. These rear curved walls may be said to constitute continuations of the curved bottoms *A A'*, and they are united to the front

wall *C* of the bucket by the converging side walls *C' C²*. These side walls and the curved rear walls, likewise the central rear wall, are gradually inclined from their top to their bottom. The central rear wall or plate *B* extends a slight distance above and below the top and bottom of the curved rear walls.

The distinctive characteristic features of the present design consist of the curved rear walls rearwardly projecting from the central flat rear wall and united to a front wall of less diameter than the rear portion of the bucket by means of converging side walls and by means of a central apex or sharp ridge, which divides the bucket into two pockets formed with curved bottoms.

Having thus described my design, what I claim as new, and desire to protect, is—

The design for a water-wheel bucket, substantially as shown and described.

In testimony whereof I affix my signature, in the presence of witnesses, this 31st day of October, 1896.

EDWARDS P. JONES.

In presence of—

N. A. ACKER,
ELMER WICKES.
